UNITED STATES PATENT OFFICE.

LAMBERT BRESSER, OF UERDINGEN-ON-THE-RHINE, GERMANY, ASSIGNOR TO THE FIRM WAGGONFABRIK A.-G., OF UERDINGEN-ON-THE-RHINE, GERMANY.

GAUGE-DRILLING MEANS.

Application filed September 26, 1925, Serial No. 58,697, and in Germany March 23, 1925.

This invention has reference to the drilling of holes and the like by means of stencils or pitch gauges, and it is intended to facilitate the drilling operation and to effect an economy in material and tools, and in particular to do away with the necessity of using special and exchangeable drilling sleeves. In the drilling operation with the aid of stencils or pitch gauges as heretofore practised, particularly for the manufacture of interchangeable structural parts of railroad cars and the like, there was the necessity of employing large quantities of drilling sleeves or collars rigidly or loosely secured in the stencils or gauges, inasmuch as there was a comparatively very large waste of these sleeves by the constant rubbing of the drill borer along the inner walls of said sleeves. Now, in accordance with my invention means are provided to dispense with the necessity of such collars or drilling sleeves, so as to effect a very substantial economy of time, labor and money in the manufacture of interchangeable structural parts and of other articles. The invention is shown in a somewhat diagrammatic manner in elevation and part longitudinal section in Fig. 1 of the drawing. Fig. 2 is a detail in elevation, substantially illustrating the fastening and releasing means which may be employed in connection with my invention.

The main shaft or spindle of the drilling machine is provided in accordance with my invention with an intermediate spindle or shaft *e* which may be mounted thereon by conical fitting or the like. This intermediate spindle *e* of suitable material carries at its free extremity the drill or borer *h*. Upon said intermediate spindle *e* a sleeve or collar *a* is slidably disposed which is provided at each end thereof with a ball bearing *b*. An outer sleeve or bearing casing *c* encloses the sleeve *a* and the bearings and is adapted to connect the ball bearings to each other and carries at one of its lower ends a detachable funnel shaped chip receptacle *f* which surrounds the drill *h* and is provided at its front end with the detachable exchangeable centering collar or bushing *g*. The diameter of the bore of this collar *g* is larger than that of the drill, so as to prevent contact thereof with the inner wall of the collar and allow the chips

to freely pass up into the receptacle *f*. The cover *d* is provided at the other, upper end of the sleeves *a* and *c* and constitutes a closing cap for the device, and it is provided with any suitable suspending or supporting or locking device.

Such supporting, locking and releasing means are shown by way of exemplification in Fig. 2 of the drawing. The entire device is suspended or supported in any suitable manner, as indicated at *p*, and carries a collar or head *l* upon which the spring-actuated levers or gripping claws *m* are pivoted at *o* the free and preferably inwardly directed or hook-shaped ends of which are adapted to become engaged with the recesses *s* of the cover *d*. The grippers *m* are under the action of the springs *n* and may be manually operated by pressure upon their outer ends *t*, so as to engage with or release the cover *d* and thereby the entire system of collars and sleeves.

The mode of operation of the device is substantially as follows:—The stencil sheet *i* carries the drilling apertures. When it is desired to carry out the drilling operation, for instance upon the piece of work *k*, by means of the stencil or gauge, the entire device is lowered and the drilling collar or sleeve *g* is introduced into the particular hole of the stencil plate *i*. Thereupon the drill shaft may be advanced into the operative position with its intermediate spindle *e* and the spiral drill *h*. After centering or starting the bore, the system *a*—*d* is again raised by being, for instance, suspended from the spring-actuating hooks *m*, while the drill is now freely exposed and centered and the chips are thereby readily discharged. The releasing and suspension device which is connected to the main spindle is free to rotate with the same. In order to be able to adapt the invention to different diameters of drilling holes, the intermediate spindle *e* is of such a size that different conical fittings may be employed for connecting the same to the main spindle or to the drill. The collar *g* may be outwardly conical.

The invention has been shown by way of exemplification only, and it should be understood that its broad principles admit of various modifications and changes of the constructional features herein described and

illustrated, without deviating from the scope and spirit of the invention, as defined in the appended claims.

I claim:—

- 5 1. In a boring or drilling tool, a rotatable spindle, a drill bit carried by the spindle, a housing slidably mounted on the spindle and in which the spindle is rotatably mounted, a chip receptacle detachably connected with the lower end of the housing, and a centering bushing at the outer end of said receptacle through which the drill bit projects, the bore of said bushing being of greater diameter than the bit for the free feed of the chips upwardly between the bit and bushing and into said receptacle.
- 10 2. In a boring or drilling tool, a rotatable spindle, a sleeve slidably engaging the spindle and in which said spindle is rotatably mounted, a housing enclosing the sleeve, anti-friction bearings interposed between the sleeve and housing above and below the horizontal center of the housing, a drill bit carried by the spindle, a chip receptacle detachably connected with the housing, and a centering bushing connected with the outer end of the receptacle, through which receptacle and bushing the drill bit extends, the bore of the bushing being of greater diameter than the bit for the free passage of the chips between the same and the bit and upwardly into said receptacle.
- 15 3. In a boring or drilling device, a rotary
- 20 spindle, a housing slidably engaging the spindle and in which the spindle is revolvably mounted, a conical chip receptacle detachably connected with the outer end of the housing, a drill bit carried by the spindle and extending through the housing, and a conical centering bushing detachably engaging the outer reduced end of the receptacle and through which the drill bit extends, the bore of said bushing being of greater diameter than the drill bit to permit the chips to pass upwardly between the same and into the receptacle.
- 25 4. In a boring or drilling device, a rotary spindle, a suspending device carried by the spindle, a collar carried by the spindle, a housing slidably mounted on the spindle for movement toward and from said collar and in which housing the spindle is rotatably mounted, a chip collecting chamber detachably connected with the lower end of the housing, and provided at its outer end with a centering bushing, a drill bit carried by the spindle and extending outwardly through the chamber and bushing, a closure at the top of the housing provided with an annularly grooved head, and spring fastening members on the collar engageable with the annular groove of the closure when the housing is slid upwardly on the spindle.

In testimony whereof I affix my signature.

LAMBERT BRESSER.
